UNITED STATES PATENT OFFICE.

CHARLES P. HENRY, OF PROVIDENCE, AND PERCY HARMER, OF CRANSTON, RHODE ISLAND, ASSIGNORS TO JAMES N. HENRY, OF PROVIDENCE, RHODE ISLAND, DOING BUSINESS AS C. P. HENRY NOVELTY COMPANY.

CURTAIN ROD.

Application filed June 5, 1922. Serial No. 565,890.

To all whom it may concern:

Be it known that we, CHARLES P. HENRY and PERCY HARMER, both citizens of the United States, residing, respectively, at Providence and Cranston, in the county of Providence and State of Rhode Island, have invented certain new and useful Improvements in Curtain Rods, of which the following is a specification.

10 Our invention refers to curtain rods and brackets, and has for its essential objects the avoidance of use of attaching screws; inconspicuousness of the attaching means; the prevention of accidental disengagement of 15 the rod from the brackets; and the attainment of these ends in a solderless, simple and inexpensive construction.

To the above ends essentially our invention consists in such parts and in such combinations of parts as fall within the scope 20 of the appended claims.

In the accompanying drawings which form a part of this specification,

Figure 1 is a plan view of our curtain rod 25 and brackets applied to the top of a window or door casing,

Figure 2, a plan view of a bracket and the adjacent portion of the curtain rod,

Figure 3, a front elevation of the bracket, 30 Figure 4, a section on line 4-4 of Figure 3, and

Figure 5, a rear elevation of the brackets.

Like reference characters indicate like parts throughout the views.

35 The curtain rod in this instance is of the hollow telescoping type comprising the sections 7-7 of resilient material and longitudinally slit as at 8 throughout their lengths, having curved end portions disposed at right 40 angles to the body portions and provided near their ends with diametrically opposite disposed perforations 10. Binding the extremities of the tubular sections 7 adjacent the perforations 10 are resilient caps 12 45 forming annular internal shoulders 13 within the rod adjacent the perforations. The caps and rod ends are yielding and resilient.

The brackets each comprise in a single 50 piece of thin metal a vertical body or plate 14 provided with a rearwardly directed flange 15 upon its upper end disposed at right angles to the body 14 and having upon

its rear end depending pointed projections 16 spaced from each other and provided upon their outer edges with inclined teeth or projections 17. Cut and bent from the material of an intermediate portion of the body 14 is an upwardly directed hook 20, below which is a flat downwardly and outwardly inclined finger 22 also cut and bent from the material of the body 14.

Each end of the rod is attachable to the bracket as follows. The hook 20 passes into the rod 7 which is initially held at an angle and projects upwardly loosely through the upper of the holes 10. The rod 7 is then pressed downward so that the cap 12 is pressed against the end of the finger 22. The yielding character of the cap 12 and end of the rod permit these portions to expand 70 under the pressure exerted by the finger, and the latter snaps beyond the shoulder 13 when the rod reaches its final horizontal position.

The brackets are applied to a door sash 75 or casing 24 by pounding the extensions 15 with an implement, and thus force the projections 16 downwardly into the wood of the sash in the upper surface of the latter, thus avoiding the use of attaching means. 80

We claim:

1. The combination of a hollow yieldable curtain rod, a yielding annular cap fixed to the end of the rod, said rod being provided with a perforation adjacent the cap, a supporting plate, a hook on the plate within the rod extendable through the perforation, and a curved downwardly and outwardly projecting finger on the plate below the hook adapted to expand the cap as it enters the rod. 90

2. As an improved article of manufacture, a curtain rod bracket, comprising in one integral element a vertical plate with a rearwardly-directed flange at its upper end having depending pointed prongs spaced from 95 said plate, said plate having stamped therefrom an upwardly-directed hook and a flat downwardly and outwardly inclined finger beneath the same both extending from the same side of the plate.

In testimony whereof we have affixed our signatures.

CHARLES P. HENRY.
PERCY HARMER.
